UNITED STATES PATENT OFFICE

2,111,681

MACHINE TOOL

Fernand Turrettini, Bellevue-Geneva, Switzerland, assignor to firm Societe Genevoise D'Instruments de Physique, Geneva, Switzerland, a firm of Switzerland

Application January 6, 1937, Serial No. 119,361
In Switzerland January 28, 1936

4 Claims. (Cl. 77—36)

The present invention relates to machine tools and particularly to drilling, boring, milling and like machine tools of the type having a slide or carriage movable along a horizontal guideway and carrying a vertically movable part, such as for example a rotatable tool spindle. Such arrangements may be used on radial drilling machines, on vertical milling machines or on jig-boring machines of the portable type.

When the vertically movable parts on such machines have large dimensions, they are usually counterbalanced by a weight suspended on a chain and disposed behind the horizontal cross beam along which moves the slide. In this case the horizontal guideway has to bear the weight of the vertically movable spindle, of the slide, and of the counterweight. This considerable weight acting on the horizontal guideway is prejudicial for the easy movability of the slide and causes increased wear of the guideway.

The object of the invention is to utilize the weight of the counterweight to partially relieve the horizontal guideway from the weight of the movable parts.

According to the invention the counterweight is carried by a lever pivotally connected to the horizontally movable slide or carriage and bearing on one or several rollers capable of rolling on a way provided along the beam carrying the horizontal slide, the reaction of the counterweight on the pivot of the lever acting to relieve the horizontal guideway from a part at least of the weight of the horizontally movable slide.

The accompanying drawings illustrate by way of example a form of construction of the invention and a modification thereof.

Figure 1 is a fragmentary vertical section of a boring machine embodying the subject of the invention.

Figure 2 is a horizontal section along the line 2—2 of Fig. 1.

Figures 3 and 4 are similar vertical and horizontal sections, respectively, of a modification of the invention.

The represented machine comprises a boring spindle 1 mounted in a quill 2, the weight of these two parts being sustained by a counterweight 3 attached to the quill 2 by means of a chain 4. This chain passes over two pulleys 7 and 8, the first one being journaled concentrically to the articulation 10 of a lever 9, and the second being carried by the free end of the lever 9. The pulley 7 could however be disposed otherwise. The articulation 10 of the lever is carried by the horizontally movable spindle head 16.

The lever 9 carries a roller 11 which rolls on a raceway 12 provided along a crossbeam 13 on which is formed the horizontal guideway 14 carrying the slide 15 and the spindle head 16.

When the ratio of the distances between the axis 10 and the roller 11, and between this roller and the pulley 8 is suitably selected, a force F will be developed at the point 10 which will balance the weight of the slide 15 with its spindle head 16.

Instead of mounting the roller 11 on the lever 9, this lever could bear on an intermediate member which would carry one or several rollers moving on the way 12.

As shown in Figs. 3 and 4, the lever 9 is supported in a carriage having a cradle-shaped member 17 and two downwardly extending flaps 18 which carry two rollers 19 movable along the raceway 12 of the cross beam 13.

I claim:—

1. In a machine tool the combination with a crossbeam having a horizontal guideway and a slide movable therealong, of a vertically movable member carried by said slide, a counterweight adapted to balance the weight of said vertically movable member, a suspension member connecting the counterweight to said vertically movable member, a lever having one end hingedly connected to said horizontally movable slide, the other end of the lever supporting the suspension member of said counterweight, and a roller supporting said lever at a point intermediate the ends thereof, said crossbeam being provided with a surface forming a raceway for said roller, whereby the reaction of the counterweight on the hinge connection of the lever will relieve the horizontal guideway from a part at least of the weight of said horizontally movable slide.

2. In a machine tool, the combination with a crossbeam having a horizontal guideway and a slide movable therealong, of a vertically movable member carried by said slide, a counterweight adapted to balance the weight of said vertically movable member, a suspension member connecting the counterweight to said vertically movable member, a lever having one end hingedly connected to said slide, a pulley carried by said slide and having its axis of rotation coinciding with the axis of the hinge connection of said lever, a second pulley carried by the other free end of the lever, said suspension member passing over said two pulleys whereby said free end of the lever supports the weight of said counterweight, and a roller supporting said lever intermediate the two ends thereof, said crossbeam

being provided with a surface forming a raceway for said roller, whereby the reaction of the counterweight on the hinge connection of the lever will relieve the horizontal guideway from a part 5 at least of the weight of said horizontally movable slide.

3. In a machine tool, the combination with a crossbeam having a horizontal guideway and a slide movable therewith, of a vertically movable member carried by said slide, a counterweight adapted to balance the weight of said vertically movable member, a suspension member connecting the counterweight to said vertically movable member, a lever having one end hingedly connected to said horizontally movable slide, the other end of said lever supporting the suspension member of said counterweight, a carriage supporting said lever intermediate the two ends thereof, said carriage having rollers, and said 10 crossbeam being provided with a surface forming a raceway for said rollers.

4. In a machine tool, the combination with a

crossbeam having a horizontal guideway and a slide movable therewith, of a vertically movable member carried by said slide, a counterweight adapted to balance the weight of said vertically movable member, a suspension member connecting the counterweight to said vertically movable member, a lever having one end hingedly connected to said horizontally movable slide, the other end of the lever being free and extending rearwardly of the cross beam, a pulley carried by 15 said slide and having its axis coinciding with the axis of the hinge of the lever, a second pulley carried by the free end of the lever, said suspension member passing over the two pulleys whereby the weight of said counterweight acts on the free end of said lever, a carriage supporting the lever intermediate the two ends of the lever, said carriage having rollers, and said crossbeam being provided with a surface forming a raceway for the rollers.
